CARD REGISTER

Nils Ivar Rosén, Stocksund, Sweden

Application June 7, 1935, Serial No. 25,463
In Sweden June 19, 1934

9 Claims. (Cl. 129—15)

This invention relates to filing devices for cards, sheets for machine bookkeeping, catalogues etc., arranged either vertically or superposed in the form of a book, and pertains more particularly to means for facilitating the turning over of the cards of the register without damaging them, for imparting stability also to very thin cards, for preventing the bases of the cards from being squeezed together, and finally, for providing visible headings without making it necessary to change cards or boxes already used, all without increasing, in a mentionable degree, the space required by the register.

With the above and other objects in view the invention is illustrated by way of example in the accompanying drawings, in which

Figure 1 is a perspective view of part of a register of cards arranged for names,

Figure 2 is a similar view of a modified form of part of a numeral register without cards,

Figure 3 shows details of a register according to Figure 1 on an enlarged scale and in transverse vertical section,

Figure 4 shows a top view of details of Figure 3,

Figure 5 is a section taken along the line V—V of Figure 4,

Figure 6 shows a variation of the detail in Figure 5,

Figure 7 shows a detail of a register according to Figure 1,

Figure 8 shows a variation of a detail of a register according to Figure 2, and

Figure 9 shows a variation of the detail in Figure 5.

Similar numerals refer to the same or similar parts throughout the several views.

In carrying out the invention there are provided parallel horizontal supporting bars or fillets 15, 15a, on which the cards 1 stand, and standards or strips 2 of steel or of some other material 2, which separate the cards, or groups of cards et cetera, from each other, and which are turnably mounted in the bottom of the register or in the back of the lying register, in rows, the strips each extending obliquely relatively to the cards et cetera and diverging more from the cards according as a greater number of cards is to be placed between two standards. If one or some cards only are to be placed between two standards the provision is made shown in Figures 1 and 2, in order to save space, by which the stationary ends of all of the strips of a row will be placed in succession in one and the same channel member 12, in which the strips are retained for ex-

ample by the walls of the channel members being resilient, or they are hingedly mounted on a common wire 11 extending through the lower ends of the strips. In order that the strips shall still be mounted in rows and shall each extend obliquely relatively to the cards the planes of the strips must in this case each form an angle with the common wire 11 or channel member 12 mentioned above, on which the strips turn. The oblique position of each strip should correspond to at least the one thickness of the strip increased by the thickness of one sheet. This arrangement, which has for its object to prevent the cards from being squeezed between the strips, is one of the most essential characteristics of the invention.

The strips or standards 2 extend outside the cards et cetera. Along part of their length at least they should overlap each other like fish-scales so as to enable one strip to move all others lying above or in front of it in the same row also if intermediate cards have been removed. On lifting a strip it is desired to prevent the subjacent strips from following and this has been obtained by providing that end of each strip, which is to be grasped, with a recess 16 in its portion extending behind the adjacent strip.

The various rows of strips are separated by means of partitions or walls consisting of one or two supports 14, which, like the strips, are mounted in the bottom and united by means of a traverse bar 6. To prevent the bases of the cards from being squeezed together between the strips and the supports 14, which would make the removal as well as the filing of cards more difficult, the walls are located parallel with the strips. This may, for example, be obtained by opposite ends of each of the supports 14 of the walls being mounted in different grooves 12 or, as in Figure 2, on different wires 11. Also this arrangement is one of the most typical features of the invention. In order to hold the channel members 12 or wires 11 together in assembled relation, the first and the last partitions of the system are fixed in their respective positions after the channel members 12 or wires 11 have been pushed together.

It does not make any difference whether the row of strips or the partition diverges relatively to the longitudinal direction of the register.

As may be seen from Figs. 1 and 2 respectively the fillets 15 may be placed either outside the supports 14 of the stirrup or inside the same.

The partition is provided with means 7 for holding headings, said means being arranged on the traverse bar 6 of the wall, as in Figures 1 and 2. 55

Furthermore, the walls are preferably provided with spacing shoulders 23, or ears, in order to guarantee an equal distance between the walls and to unload the pressure from the cards on the partitions. The shoulders may be formed by the supports, which are bent back around the traverse bar 6, possibly above the bar 6 to about on a level with holder 7. If the supports of the partition extend within the surface of the card, the bar 6 may lie outside the card instead, by which the wall will not encroach upon the depth of the card register, provided that its supports have about the same thickness as the strips. This is also a typical feature of the invention.

15 In certain cases one single support is sufficient to hold the wall. The outer end of the strips, which extends outside the card, may be provided with or it may be formed as a name, numeral or color index, see Figures 1, 7 and 8. Sometimes, however, the index of the card may be placed on the partition, for example, in numeral registers as in Figure 2. But also name registers may be constructed in a similar way, i. e. with stationary standards without indexes, each pointing at its special name plate, which is replaceable and, if desired, slidably disposed on the bar 6. Indications, if any, which for example are meant to indicate a month 17 of maturity or meant to indicate that several cards are placed behind one and the same standard or strip, are inserted in the transparent pocket 3 for holding the headings or such indications may be outlined on the cards or on the strip themselves by outlining the desired number by punching holes in the cards or strips as shown in Fig. 8. In less complicated registers, in which the strips are made in one single piece the name plates, too, may be secured in a similar manner. Especially in numeral registers the indications may also be placed on the bars 6.

40 The construction of the bases of the strips may vary. Either, they may be made integrally with the strips, Figures 2 and 9, or each base may consist of a hollow cylinder 4 having an oblique cut for introducing the strip.

45 A suitable construction of the channel members 12 is illustrated in Figure 5. In this figure these members are formed by channel members made of flexible steel. A metal wire 18, each end of which is bent to a loop, is placed in the bottom of the channel, where it is retained by recesses 19 provided in the walls of the channel. The object of the wire with its bent loop is to prevent the channels from pressing against each other, when the register is moved in the slide 50 grooves 20 in the longitudinal direction of the register, and also to make it possible to mount the stationary end of the strip in a suitable manner, and further to prevent too strong stresses on the channels 12 when removing or applying 55 strips, and finally, to make it possible to remove and apply the rows of strips anywhere in the register. Figures 3, 4 and 5 show details hereof.

60 When an additional channel member is to be applied, space is first made for the same by means of a wedge, which is inserted between the loops of two adjacent channel members. In case the register is of large depth, the wedging action is applied between a plurality of loops consecutively. After that one end of the added channel is inserted in the groove 20 of bar 15. Then the other end of the channel member is attached to the bar 15a by sliding the tubular end 21 of the front support 14 into the groove 20 of the bar 15a. This is permitted, due to the fact that the end 21 telescopes or slides within the front end of the chan-

nel member or within the tubular lower end of the front one of the standards 2.

In numeral registers having a wire extending through the bases of the strips, Figure 2, the rows of strips are retained or released by the wire 5 proper 11 being sprung up and like a bolt pulled below or out from under the fillets 15, on which the cards stand.

The bases of the strips and of the supports are provided with recesses 22, the object of which is 10 to prevent the adjacent strip from being displaced when one strip is being lifted and also to make it possible to place more cards than one between two strips standing in one and the same groove without their bases being squeezed by the 15 same.

When a very great number of cards or catalogues and the like are to be placed between two strips, the row of strips is placed in two or more channel members 12 or on two or more metal 20 wires 11, besides which the stationary ends of the strips preferably are fixed in a correct lateral position relative to one another by means of sockets placed in the channel member or thread- 25 ed on the wire.

The bars 15, 15a, on which the cards stand, may be placed either inside the supports 14 (Fig. 2) or outwardly of the same (Figs. 1 and 3). In numeral registers (Fig. 2) having only nine strips in each row it is easy to provide room for the bars 30 15, 15a, between the two supports 14 and the two outermost strips of the row and, moreover, it is easy to place them there on account of their simple construction. In name registers (Figs. 1 and 3) on the other hand, in which it is desired to 35 have as many strips as possible in each row, and in which it is necessary to give the bars 15, 15a, a more complicated construction, the bars should be placed outwardly of the supports 14.

Displacement of the channel members 12 trans- 40 versely of the register is prevented by the bars 15, 15a, in the construction shown in Figs. 1 and 3. In the numeral register shown in Fig. 2 and intended to be placed in a common card box, the displacement of the wires lengthwise thereof is 45 prevented by the side walls of the said box. Displacement of the channel members lengthwise of the bars 15, 15a, is prevented by any suitable means. For example, after the channel members 12 or wires 11 have been pushed together, they 50 are fixed in their positions by stopping pins 25, (Fig. 2) which are inserted in holes 26 suitably spaced from each other in the bars 15, 15a, at the end of the register or both at the beginning and the end of the register; these pins being of sufficient length as to extend below the bars and rest 55 against the end portions of the channel members or wires so as to prevent displacement of these members in the longitudinal direction of the register.

Two longitudinally extending strips 24 of metal, which, at both ends of the register, are rigidly secured with each other and with the bars 15, 15a, by means of transverse bars 27, support the channel members or the strips mounted on the wire. 60 They form carrying elements, when, for example, the register according to Fig. 2, is to be placed in a common card box or to be removed from such a box.

The outermost partitions are made as strong 70 covers, the object of which is, inter alia, to fix the angle of inclination of the strips, and one of which at least should be adapted to be fixed in various positions so as to make it possible to change the number of rows of strips, and both 75

should be adapted to be moved in order to make is possible to transfer simultaneously from one register to another a substantial part of the register. This part, which is simultaneously moved 5 to the outermost ends of the fillets 15 may be lifted out of the register by the protruding part of the fillet 15 being cut away at some place.

Having now described my invention, what I claim as new and desire to secure by Letters 10 Patent is:

1. A register for loose cards or the like, arranged one behind the other comprising a base for supporting the cards, a plurality of narrow strips adapted to be arranged between said cards 15 and having their inner ends swingably mounted on said base, said strips being adapted to extend from said base beyond the outer edges of the cards, and arranged adjacent and obliquely behind each other in rows, the planes of the strips 20 in each row forming an acute angle with the longitudinal direction of the row.

2. An arrangement according to claim 1, in which the strips cover each other along part of their length like fish-scales, so that when lifting 25 one strip all other strips above it in the same row will also be lifted.

3. An arrangement according to claim 1, in which the base is provided with grooves having their side walls arranged a predetermined distance from each other, and the inner ends of all 30 the strips of the same row are swingably disposed in succession in one of said grooves, and slideable in the longitudinal direction of said groove, the plane of each strip forming an acute angle with the 35 longitudinal direction of said groove.

4. An arrangement according to claim 1, including metal wires, each wire supporting all of the strips of the same row, said wires extending through the inner ends of the strips, whereby the latter are swingably mounted on said wires, the plane of each strip being oblique to the axis of the wire and forming an acute angle with the longitudinal direction of said wire.

5. An arrangement according to claim 1, in which the outer end of each strip is provided with a recess in the portion of the strip extending behind an adjacent strip, so that the grasping 45 flaps formed by said recesses lie beside each

other, whereby the operator may grasp one of said flaps at a time.

6. A register for cards or the like, comprising a base for supporting a plurality of rows of cards, channels mounted on said base and having inwardly diverging resilient side walls, the upper edges of said walls being spaced from one another to provide an opening at the upper surface of each of said channels, a plurality of narrow strips adapted to be arranged between 10 the cards in each row and having their inner ends swingably mounted in said channels, the width of the opening in each channel being smaller than the width of the inner ends of the strips, whereby said strips will be held in said channels 15 by said side walls, said strips being adapted to extend from the base beyond the outer edges of the cards in each row and arranged adjacent and obliquely behind each other in rows, the planes of the strips in each row forming an 20 acute angle with the longitudinal direction of the row.

7. An arrangement according to claim 1, including a channel mounted on the base and having inwardly diverging flexible side walls, said 25 channel having a groove provided between the upper edges of said side walls adapted to receive the inner ends of all the strips in one row, and reinforcing means for the side walls of the channel arranged within the channel and supporting 30 the inner ends of said strips.

8. An arrangement according to claim 1, including partitions for separating the rows of strips from each other, each of said partitions being swingably mounted on the base and consisting of a substantially inverted U-shaped member, the transverse bar of said member being adapted to engage the upper ends of the strips of the adjacent row.

9. An arrangement according to claim 1, including partitions for separating the rows of strips from each other, each partition being swingably mounted on the base and consisting of a substantially inverted U-shaped member, the transverse bar of said member being adapted to engage the 45 upper ends of the strips of the adjacent row, the swing axis of said partitions forming an acute angle with the swing axis of the strips in a row.

NILS IVAR ROSEN.
